CAR DUMPING MECHANISM

Alfred C. Schmohl, Beaver Falls, Pa., assignor,
by mesne assignments, to Koppel Industrial
Car and Equipment Company, McKees Rocks,
Pa., a corporation of Pennsylvania

Application May 8, 1931. Serial No. 535,891

8 Claims. (Cl. 214—64)

My invention pertains to cars of the type known as quarry cars which have the body tiltably mounted on the underframe but no provisions for tilting the car body. It is to be understood, however, that my invention can be used equally as well with cars of any type in which the body is tiltably mounted and the doors may be of the type known as lift doors which move upwardly and outwardly away from the car body as the body is tilted or with cars having the doors pivotally mounted adjacent the floor of the body and opening downwardly and outwardly to form aprons to discharge the lading away from the sides of the track upon which the car is mounted.

15 An object of my invention is to provide a means for tilting the body of a dump car, said means being fixed adjacent one side of the track upon which the cars are mounted and to which the cars are moved for dumping.

20 Another object of my invention is to provide a dumping mechanism which will maintain control of the body throughout the entire dumping and righting movements thereof and which, when in idle position, is free of the body of the car.

25 Referring now to the drawings, Fig. 1 shows in elevation a preferred embodiment of my invention; Fig. 2 shows in elevation the position of the mechanism when the car body is moved to fully tilted position; Fig. 3 is a section taken along the lines 3—3 of Fig. 1.

Referring now in detail to the drawings, reference character 1 indicates a dumping mechanism mounted adjacent one side of a track 2 on which is mounted a dump car having a tiltably mounted body 3.

The dumping mechanism comprises a supporting frame 4 preferably formed of structural steel shapes for greater durability and strength. 40 Mounted on trunnions 5 and supported between the members 6 of the frame work is a body actuating member 7 comprising a reciprocating member 8 mounted within a cylinder 9 and actuated therein by fluid pressure. One end of the member 8 has a suitably shaped end portion 10 for engagement with a convenient portion of the car body such as 11. Flexibly connected to the cylinder 9 is a suitable source of supply of fluid under pressure for actuating the member 8, which 45 source of supply forms no part of my invention and is not shown in the drawings.

Mounted on the support 4 and adjacent to the cylinder 9 is a buffering and guide member 12, which is preferably pivotally mounted on a support 13 so that it may be swung upwardly and

away from the cylinder 9 into the position shown in dot and dash lines of Fig. 1 of the drawings for a purpose which will be described as the specification proceeds. This member 12 preferably comprises a suitably shaped casing with 60 in which is mounted the buffering member 14, which is resiliently urged outwardly by a spring 15.

Referring to Figs. 1 and 2 of the drawings, it will be noted that the arrangement of the members 9 and 12 is such that when the member 12 is moved to idle position, as shown in dot and dash lines of Fig. 1, the cylinder 9, by reason of its weight, would assume a vertical position as indicated in dot and dash lines and provide greater 70 clearance between the mechanism and the car mounted on the adjacent track. When the member 12 is moved into the position shown in full lines of Fig. 1, the member 14 holds the cylinder 9 in a position, such that the upward movement of the member 8 within the cylinder 9 will cause the portion 10 to engage with the bearing 11 of the car body. When the body has been moved to fully tilted position and the cylinder 9 in the position shown on Fig. 2 of the drawings, 80 the cylinder has moved out of engagement with the member 14 and upon return of the body to a horizontal position, the member 14 engages with the cylinder 9 and acts as a buffer and stop. The resilient member 15 within the member 12 85 absorbing any shocks caused by the engagement of the member 14 with the cylinder 9.

When the car body is moved to fully tilted position to discharge the lading, and particularly with the type of car shown in the drawings, it is 90 preferable to have some means to maintain the member 8 in engagement with the car body so as to facilitate the return of the body to a horizontal position and to prevent any damage to the car body and mechanism which might be caused by 95 their becoming disengaged before the body has fully returned to a horizontal position. Such a means is provided by the latch member 16 which is mounted on the portion 10 of the member 8 and which is adapted to engage with the car body 100 and secure the member 8 thereto. One means of operating this latch member is shown in the drawings in the form of a counterweight 17 mounted on the support 4 and connected to the latch member 16 by means of the flexible chain 105 or rope 18. It will be observed that as the body actuating member 8 of the dumping mechanism moves upwardly to tilt the body to discharge the lading, the counterweight 17 is moved upwardly by means of the connecting member 18 and in so 110

doing causes the latch member 16 to rotate on its pivot 19 and to engage with the portion 11 of the car body as shown in Fig. 2 of the drawings. As the arrangement of the counterweight 17 and cylinder 9 is such that the counterweight does not come to rest on its base 21 of the frame work until the body has completed its return movement, the latch 16 will be held into engagement with the member 11 throughout the entire tilting and righting movements of the car body. In order to provide for the separation of the body tilting member and car body after the righting of the car body, a tension spring 20 or any other suitable means is connected to the latch 16 and member 8 so that when the latch is free of the weight of the member 17, the member 20 rotates the latch into a position free of the member 11.

Referring to Fig. 2 of the drawings it will be noted that when the arm of the dumping mechanism is fully extended it is above the antifriction device over which the flexible chain or rope 18 is passed to engage with the counterweight. If desired, this counterweight can be made of sufficient size so that upon exhausting the pressure from the cylinder 9 it will assist in the return of the member 8 and provide for the righting of the car body.

With some types of cars, the body, after the discharging of the lading and the reduction of pressure within the cylinder 9, would automatically right itself and in so doing, return the member 8 from the position shown in Fig. 2 to that shown in Fig. 1. When, however, the construction of the body is such that it will not automatically right itself by reason of its own weight and the large sized counterweight is ineffective or undesirable, the member 8 can be moved inwardly of the cylinder 9 under fluid pressure. In order to do this a pressure line can be attached to the upper end of the cylinder and a suitable valve provided to direct the flow of pressure into the cylinder.

Having thus described the invention what I claim as new and desire to secure by Letters Patent is:

1. In a dumping mechanism for a car having a tiltably mounted body, a fluid pressure actuated body tilting member, means for maintaining said member in position to engage with said body and means operatively associated with said member to maintain said member and body in engagement throughout the entire dumping and righting movements of said body.

2. In a dumping mechanism for a car having a tiltably mounted body, a fluid pressure actuated body tilting member mounted adjacent one side of said car and out of engagement therewith, means on said member for engaging with said body, and resilient means independent of the car for guiding said member into engagement with said body.

3. In a dumping mechanism for a car having a tiltably mounted body, a body tilting member, said member being contained within a cylinder mounted on trunnions adjacent one side of said car, and actuated by fluid pressure so as to have a reciprocating movement within said cylinder, a member mounted on said body tilting member and actuated by the movement thereof to automatically secure said body tilting member to said car body throughout the entire tilting and righting movements of the body.

4. In a dumping mechanism for cars having

tiltably mounted bodies and without self contained means for actuating said bodies, said device being positioned adjacent one side of the tracks upon which said cars are mounted and comprising a fluid pressure actuated body tilting member contained within a cylinder mounted on trunnion so as to provide a limited rotation in a direction transversely of the car, a member for selectively moving said cylinder and body tilting member into operative position and a member operatively associated with said body tilting member and controlled by the movements thereof to maintain said body tilting member and car body in engagement while the car body is out of normal load carrying position.

5. In a dumping mechanism for cars having tiltably mounted bodies but no means for actuating same, said device being positioned to one side of the tracks upon which the cars are mounted and normally free of said cars, said device comprising a body actuating member contained within a cylinder mounted on trunnions to permit limited rotation thereof, said member having a reciprocating movement within said cylinder and under fluid pressure, a suitably shaped end portion on said member to engage said body as the member moves upwardly towards the body, a latch member mounted on said end portion and adapted to secure said actuating member and car body in engagement and a counterweight secured to said latch member for operating said latch member by movement of said body actuating member.

6. In a dumping mechanism for cars having tiltably mounted bodies but no means for actuating same, said mechanism being positioned to one side of the tracks on which the cars are mounted and normally free of said cars and comprising a cylinder mounted on trunnions adjacent said tracks, a body actuating member mounted in said cylinder and adapted to move outwardly and upwardly to effect the tilting of the body of said car, a latch member mounted on said body actuating member to secure said member and car body in engagement throughout the dumping and righting movements of said body, and gravity actuated means operatively associated with said body actuating member and latch for controlling the movements thereof.

7. In a dumping mechanism for cars having tiltably mounted bodies and without self-contained means for tilting the body in combination, a fluid-pressure actuated member contained within a cylinder mounted free of the car adjacent one side thereof, resilient means operatively connected with said cylinder for guiding said member during the tilting of said car body and means operatively associated with said member and actuated by the movement thereof to retain said member in engagement with said body throughout the tilting and righting movements thereof.

8. In a dumping mechanism for cars having tiltably mounted bodies and without self-contained means for actuating said bodies, said mechanism being positioned adjacent one side of the tracks from which the cars are mounted and comprising a cylinder mounted on trunnions, a reciprocating member within said cylinder and resilient means associated with said cylinder maintaining the portion of the reciprocating member in engagement with the body and the cylinder trunnions, in alignment throughout the tilting movement of the car body.

ALFRED C. SCHMOHL
